UNITED STATES PATENT OFFICE.

BRUNO VON BÜLTZINGSLÖWEN, OF NEW YORK, N. Y.

ADVERTISING SIGN.

Application filed May 11, 1922. Serial No. 560,103.

To all whom it may concern:

Be it known that I, BRUNO VON BÜLTZINGSLÖWEN, a citizen of the United States of America, residing at New York, in the county of Bronx and State of New York, have invented certain new and useful Improvements in Advertising Signs, of which the following is a specification.

The present invention relates to electric or other signs used for advertising purposes and has for its object to provide a simple and comparatively cheap sign frame in which individual characters, such as letters, numbers, figures or the like can be removably and adjustably supported to enable various changes in the wording or display of the sign.

Another object is to provide means whereby the exchange of characters or the adjustment thereof in the sign can be effected very easily and quickly.

With these and other objects in view my invention consists in the novel construction, combination and arrangement of parts as will be hereinafter more fully described and defined in the appended claims.

In the accompanying drawings in which similar references denote corresponding parts, Fig. 1 is a front view of one form of construction of my new sign; Fig. 2 is a vertical section thereof; Figs. 3 to 6 are enlarged similar sections to Fig. 2 each showing slight modifications of a detail; Fig. 7 is a front view of a character plate; Fig. 8 is a front view of a modified construction of the sign; Fig. 9 a vertical section thereof; Figs. 10 and 11 are enlarged sections similar to Fig. 1; Fig. 12 a front view of a character frame; Fig. 13 a side view thereof; Fig. 14 a top plan view of two contiguous characters and Fig. 15 a cross section on line 15-15 of Fig. 12.

Referring first to the construction shown in Figs. 1 and 7, the sign comprises a frame 10 of any desired shape (in the present example rectangular), made of wood or other suitable material and in form of a box or casing. The interior of the casing may according to requirement be divided horizontally in compartments by partitions 11 and in each compartment there may be provided sockets 12 for electric bulbs 13.

In front the frame or casing has an opening or openings 14, one for each compartment, said openings 14 extending longitudinally throughout the length of the compart-

ments. In the bottom face of the top or upper ledge 15, as well as of the intermediate ledge or partition 11 near the front edges thereof, grooves 16 are provided extending 60 throughout the length of the opening, while the upper face of the intermediate ledge 11 and that of the bottom or lower ledge 17 of the frame are recessed to form shoulders 18 extending in alinement with the rear 65 edges or walls of the groove 16. These grooves 16 and recessed parts serve as bearings for individual characters such as letters, numerals or the like which are adapted to be removably and adjustably supported 70 in said frame. The characters may be just ordinary rectangular plates with a letter, number or the like painted or embossed thereon, but I prefer to use characters, each consisting substantially of a box shaped 75 frame 19 of suitable material, the front and rear walls of which have openings conforming with the contour of a letter, numeral or other character and between which walls a plate 20 of semi-transparent material, as a 80 colored glass, is removably supported, as best shown in Figs. 12 and 13. Such construction is fully described in a separate application. The grooves 16 are made of such depth, that the height between the top of a 85 groove and the recessed part of the bottom of the compartment is slightly larger than the height of the frame 19 of the character, so that the latter can be conveniently positioned or removed, by raising it inwardly 90 into the groove and off the supporting face or ledge and swinging it in an inclined position outwardly. To hold the individual characters 19 in adjusted position within the sign frame and enable their simultaneous 95 locking and unlocking, I provide the following means: Extending longitudinally through each compartment and rotatively borne in the side walls 10', of the frame 10, is a horizontal spindle 21. At one side of 100 the frame the spindle 21 carries on its outwardly projecting end a crank arm 22 which through a lock pin 23 adapted to engage a notch or bore 10² in the respective side wall of the frame 10 can be locked in a certain 105 position.

The spindle is adapted to extend a suitable distance away from the rear faces of the character frames 19 and has fixed thereon throughout its length a plurality of equidistantly arranged hook-shaped members or arms 24, the spacing between said arms 24

being equal to the width of a character frame 19. Projecting from and fixed to the rear face of each character frame is a catch 25 arranged so that when the spindle 21 is swung in a certain direction the hooks 24 thereof will engage said catches 25 and thereby lock the character frames in position.

For very long signs it is advantageous to provide guides for the hooks 24 in order to insure the simultaneous engagement with the catches 25 of the characters 19. Such guides are shown in Figs. 3 and 4 to consist of brackets 26 fixed to the bottom of each compartment and provided with circularly curved recesses or grooves 27 in which the hooks 24 are guided. The catches 25 according to Figs. 2 and 3 are angular in shape. In Fig. 4 the catch 25' is shown curved. Instead of using rigid catches, such as 25, 25', I may use snappers or latches 25² as shown in Fig. 5, pivoted to the rear of the character frames as at 25². In Fig. 5 the guide members 26' are shown fixed to the rear wall of the sign frame 10.

In Figs. 5, 6 and 7 the character is shown in form of a rectangular plate 28 with the letter, number or the like 29 embossed thereon.

The characters may be secured in position by frictional engagement of arms 30 fixed to the spindle 21 with a cross rib 31 projecting from and fixed to the rear of the character 28, as shown in Figs. 6 and 7.

In the sign construction shown in Figs. 8 and 9 the frame 32 is divided into a number of vertically superposed tiers. Instead of the fastening means shown in Figs. 1-6 there is a vertically swinging ledge or bar 33 arranged in front of each compartment extending throughout the length of the latter and hinged or otherwise pivotally secured to the frame. When swinging upwardly this ledge is adapted to bear against the lower portions of the character frames 19 or plates 28 and hold them steady in position, the characters 19 or 28 being borne in the grooves 16 and on the recessed part of the bottoms of the compartments in the aforescribed manner.

The ledges 33 may be held in operative position by set screws 34 engaging notches in the side walls of the frame 32 and carried by end arms 35 projecting from said ledges.

Instead thumb screws 36 may be used, which are screwed in the side walls of the frame and the arms may be hook-shaped as at 35' to engage said thumb screws, as shown in Figs. 10 and 11.

In order to hold the character plates or frames in proper alignment and adjustment in the sign frame the same are cut out or grooved at their sides or if made of two superposed sections the said sections are transversely displaced relative to one another so that contiguous characters will overlap one another, as shown in Figs. 14 and 15.

To facilitate the positioning and the removal of the character plates or frames from the sign frame, I provide extra boards or plates 37 which are adapted to be located at the ends of each tier, and which may be provided with forwardly projecting knobs or the like 38. Prior to removal or insertion of the character plates these end plates 37 are removed.

Sign frames constructed in the aforescribed manner permit the wording and the display to be changed easily and in comparatively short time.

What I claim is:—

1. An advertising sign comprising a box shaped frame, individual character members removably and adjustably supported in said frame, a catch at the rear of each character frame, and common rotary means supported in said frame and members carried by said common means to engage said catches and thereby lock said character frames in position.

2. An advertising sign comprising a box shaped frame, individual character members removably and adjustably supported in said frame, a catch projecting from the rear of each character member, a spindle extending longitudinally through the frame and operable from the outside of the latter and means carried by said spindle to engage the catches of said character members and lock the latter in position.

3. An advertising sign comprising a box shaped frame, individual character members removably and adjustably supported in said frame, a catch projecting from the rear of each character member, a spindle extending longitudinally through the frame and operable from the outside of the latter, hooked members carried by said spindle and adapted to engage said catches, and guides for said hooked members.

In testimony whereof I affix my signature in presence of two witnesses.

BRUNO von BÜLTZINGSLÖWEN.
